UNITED STATES PATENT OFFICE

163,992

GRILLE FOR AN ACCORDION OR SIMILAR ARTICLE

Alfred Dronge, New York, N. Y.

Application October 31, 1950, Serial No. 12,795

Term of patent 3½ years

(Cl. D56—1)

To all whom it may concern:

Be it known that I, Alfred Dronge, a citizen of the United States of America, residing in New York, county of Bronx, and State of New York, have invented a new, original, and ornamental Design for a Grille for an Accordion or Similar Article, of which the following is a specification, reference being had to the accompanying drawing, forming part thereof,

Fig. 1 is a plan view for a grille for an accordion or simiar article showing my new design.

Fig. 2 is an edge view thereof.

I claim:

The ornamental design for a grille for an accordion or similar article substantially as shown.

ALFRED DRONGE.
